UNITED STATES PATENT OFFICE.

AUGUST C. KREITZER, OF HUMBOLDT, KANSAS.

LIQUID-FUEL BURNER.

1,382,655.

Specification of Letters Patent. Patented June 28, 1921.

Application filed April 14, 1920. Serial No. 373,862.

To all whom it may concern:

Be it known that I, AUGUST C. KREITZER, a citizen of the United States, residing at Humboldt, in the county of Allen and State 5 of Kansas, have invented new and useful Improvements in Liquid-Fuel Burners, of which the following is a specification.

This invention relates to liquid fuel burners which are designed to spray or inject 10 oil or other liquid fuel and steam into the combustion chamber of a furnace, and its object is to provide a novel and improved burner of this type which will take heavy and dirty crude oil without clogging up, 15 and which produces a large flame of intense heat.

The invention also has for its object to provide a burner of the kind stated which can be easily cleaned without removal from 20 the furnace, and which is economical in fuel consumption, and readily regulated.

The objects stated are attained by means of a combination and arrangement of parts to be hereinafter described and claimed, and 25 in order that the same may be better understood, reference is had to the accompanying drawing forming a part of this specification.

In the drawing,

30 Figure 1 is an elevation of the burner; Fig. 2 is a central longitudinal section thereof, partly broken away, and

Fig. 3 is a plan view of a burner tip.

Referring specifically to the drawing 5 35 denotes the casing of the burner, the same being a tube of suitable length having fitted to its forward end a discharge nozzle, and provided at its rear end with a fuel and steam connection. This connection is made 40 by fitting the rear end of the tube with a T-coupling 6 into one end of which the tube is screwed, with a plug 7 seating in the opposite end of the coupling. To the side of the coupling member is attached a steam delivery pipe 8, and to the plug 7 is connected 45 a fuel delivery pipe 9.

Mounted centrally within the tube 5 is a pipe 10 which carries the fuel to the nozzle of the burner, the forward end of the pipe 50 discharging into the nozzle, and its rear end being connected to the pipe 9 where it screws into the plug 7. Oil or other liquid fuel flows through the pipe 10 to the nozzle, and steam entering the coupling member 6 flows 55 through the tube 5 to the nozzle, the diameter of the pipe 10 being less than that of

the tube 5, so that it is spaced from the latter. The hot steam surrounding the fuel pipe 10 heats said pipe and the fuel flowing therethrough so that it flows freely and 60 is also partly vaporized.

The nozzle comprises a tubular main body 11 to the rear end of which is secured a cap 12 tapered toward its rear end and having said end extending into the forward end of 65 the tube 5 for a short distance. The cap 12 is screwed into the nozzle body 11 and it is fastened to the tube 5 by a coupling nut 13.

To the rear end of the cap 12, where it seats in the tube 5, in spaced relation therewith, is connected the fuel pipe 10, so that 70 the fuel is discharged through the cap into the nozzle body 11. In the side of the cap 12 are ports 14 establishing communication between the inside of the cap and the steam 75 space in the tube 5 around the pipe 10. It will therefore be seen that steam and liquid fuel are discharged into the cap 12, from which latter the same pass into the nozzle body 11, the latter forming a mixing chamber 80 in which the steam and fuel thoroughly commingle. The wall of the cap 12 in which the ports 14 are located is flared forwardly, and said ports are arranged obliquely with respect to the longitudinal axis 85 of the cap 12, which results in a discharge of steam jets obliquely across the stream of fuel entering the cap from the pipe 10. This results in the fuel being caught and whirled around by the jets of steam, so that in its 90 passage through the nozzle body or mixing chamber 11 it is transformed practically into a gas.

To the forward end of the nozzle body 11 is secured a nipple 15 having a reduced 95 outer end to which a burner tip 16 is secured.

Immediately back of the nipple 15, and opening thereinto, the nozzle body 11 seats a conical deflector member 17 having a central port 18 and side ports 19. This member is hollow and its apex points rearwardly, with the port 18 opening into the center of the nozzle body 11. The interior of the member 17 is flared forwardly, and the side 100 ports 19 are located to discharge obliquely thereinto.

The mixture of oil and steam transformed into a highly combustible gas in the nozzle body or mixing chamber 11 passes through 110 the ports 18 and 19 into the deflector member 17, from which it passes through the

- 2
- nipple 15 to the tip 16 and is discharged from the latter. The gaseous mixture passing through the ports 19 is discharged in an oblique direction with respect to the stream 5 entering the member 17 by the way of the center port 18, which produces a further commingling of the fuel particles. The pressure is also reduced owing to the flare of the member 17, and the fuel mixture is discharged from the tips 16 in a gentle wide spread, so that it burns close to the tip. The flame is white and has an intense heat, and combustion takes place with practically no smoke.
- 15 The steam supply pipe 8 is equipped with two valves 20 and 21, respectively, and between said valves, a branch 22 is connected to the fuel delivery pipe 9. A fuel supply pipe 23 is connected to the pipe 9 and has 20 a valve 24. In the branch 22 is interposed a valve 25.

To operate the burner, the valve 25 is closed, and the valves 20, 21 and 24 are opened, whereupon the oil or other liquid 25 fuel enters the pipe 10, and steam enters the tube 5. If the oil is very thick and dirty, the valve 25 is opened more or less so that some steam is also delivered into the fuel pipe 10. If the burner needs cleaning, the valve 30 20 may be closed and the valve 25 opened, to let the whole pressure go through the pipe 10, and this can be done without removing the burner from its place in the furnace.

I claim:

- 35 1. In a liquid-fuel burner, a tubular member, a fuel pipe in said member and spaced from the interior wall thereof, a steam supply connection to the tubular member, a fuel connection to the fuel pipe, a mixing 40 chamber at the outlet end of the tubular member and the fuel pipe, a hollow member connecting the tubular member and the mixing chamber, the interior of said hollow member being flared toward the mixing 45 chamber, said hollow member having side ports establishing communication with its interior and the tubular member, and the fuel pipe discharging centrally into the hollow member, the side ports being oblique to 50 discharge in an oblique direction across the interior of the hollow member, a hollow deflector member seating in the outlet end of the mixing chamber and having a forward flare, said deflector member also having a central port and oblique side ports 55 establishing communication between the interior of the mixing chamber and the interior of the deflector member, said side ports being

out of alinement with respect to the first-mentioned side ports, and a nozzle tip having 60 a connection with the interior of the deflector member.

2. In a liquid-fuel burner, a tubular member, a fuel pipe in said member and spaced from the interior wall thereof, a steam supply connection to the tubular member, a fuel connection to the fuel pipe, a mixing chamber at the outlet end of the tubular member and the fuel pipe, a connection between the mixing chamber, the tubular member 70 and the fuel pipe, said connection having steam and fuel port for admitting steam and fuel into the mixing chamber, the fuel port being positioned to discharge centrally into the mixing chamber, and the steam ports 75 being positioned to discharge obliquely across the stream of fuel delivered through the fuel port, a nozzle tip on the outlet end of the mixing chamber, and a hollow deflector member in the mixing chamber back 80 of the nozzle tip, said deflector member having a central port and oblique side port establishing communication between the interior of the mixing chamber and the interior of the deflector member, said side ports 85 being out of alinement with respect to the aforesaid steam ports.

3. In a liquid-fuel burner, a tubular member, a fuel pipe in said member and spaced from the interior wall thereof, a steam supply connection to the tubular member, a fuel connection to the fuel pipe, a mixing chamber at the outlet end of the tubular member and the fuel pipe, a connection between the mixing chamber, the tubular member and 90 the fuel pipe, said connection having steam and fuel ports for admitting steam and fuel into the mixing chamber, the fuel port being positioned to discharge centrally into the mixing chamber, and the steam ports 95 being positioned to discharge obliquely across the stream of fuel delivered through the fuel port, a nozzle tip on the outlet end of the mixing chamber, and a hollow deflector member in the mixing chamber back 100 of the nozzle tip, said deflector member having a central port and oblique side ports 105 establishing communication between the interior of the mixing chamber and the interior of the deflector member, said side ports 110 being out of alinement with respect to the aforesaid steam ports, and said interior of the deflector member having a forward flare.

In testimony whereof I affix my signature.
AUGUST C. KREITZER.
